US00D923169S

(12) **United States Design Patent** (10) **Patent No.:** **US D923,169 S**
(45) **Date of Patent:** **** Jun. 22, 2021**

(54) **CIRCUIT KIT FOR A HUMIDIFIER**

(71) Applicant: **Fisher & Paykel Healthcare Limited**,
Auckland (NZ)

(72) Inventors: **Kiel Anthony McCool**, Auckland (NZ);
Callum McDonald Ross, Auckland (NZ)

(73) Assignee: **Fisher & Paykel Healthcare Limited**,
Auckland (NZ)

(**) Term: **15 Years**

(21) Appl. No.: **29/717,926**

(22) Filed: **Dec. 19, 2019**

Related U.S. Application Data

(62) Division of application No. 29/674,255, filed on Dec. 20, 2018, now Pat. No. Des. 874,654, which is a division of application No. 29/541,180, filed on Sep. 30, 2015, now Pat. No. Des. 841,147.

(57) **CLAIM**

The ornamental design for a circuit kit for a humidifier, as shown and described.

DESCRIPTION

FIG. 1 is a top, front, and left side perspective view of a circuit kit for a humidifier showing our new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

Broken lines are used to illustrate features of the circuit kit for a humidifier which form no part of the claimed design.

1 Claim, 4 Drawing Sheets
